UNITED STATES PATENT OFFICE.

THOMAS LEGGETT STURTEVANT, OF QUINCY, MASSACHUSETTS, ASSIGNOR TO STURTEVANT MILL COMPANY, A CORPORATION OF MAINE.

SCREEN OR SEPARATOR.

1,125,762.

Specification of Letters Patent.

Patented Jan. 19, 1915.

Application filed October 7, 1914. Serial No. 865,466.

To all whom it may concern:

Be it known that I, THOMAS L. STURTEVANT, a citizen of the United States, residing at Quincy, in the county of Norfolk and State of Massachusetts, have invented or discovered certain new and useful Improvements in Screens or Separators, of which the following is a specification, reference being had therein to the accompanying drawing.

This invention relates to the screens or sieves of separators, and means for supporting same, the invention being particularly intended for use in that class of separators in which the screens or sieves are supported resiliently in an inclined position and are jarred or vibrated by the percussive action of hammers.

The present invention has for its principal object to provide screens which in themselves have great resilience and which comprise metallic frames and fine mesh wire cloth stretched thereon, the improved screens being of such construction that they will be light, durable and at the same time inexpensive. The frames of the improved screens preferably comprise elastic strengthening and stretching bars which may be bowed downwardly or outwardly away from the wire mesh screen clothing and which will be so attached to the side bars of the screen frames as to have a tendency to stretch the wire mesh screen clothing and hold it taut. To this end each rectangular screen frame preferably comprises side bars and end bars of angle-iron joined together at their corners where they may be provided with triangular sheet metal fastening corner pieces. Each screen comprises, between its end bars, a series of resilient cross bars the ends of which are sprung into place in such a manner as to impinge against the vertical flanges of the angle-iron side bars, and notwithstanding that these cross bars may be attached to the horizontal flanges of the side bars they will tend to press the side bars outward and will thus serve to hold the wire mesh screen clothing taut, and the strain of their outward pressure will be exerted against the vertical flanges of the side bars in such a manner as very largely to relieve their attaching rivets from strain. The screens are preferably supported on the

inclined separator frame by means of angle-irons forming inclined channels, and the vertical flanges of which angle-irons are loosely overlapped by the vertical flanges of the side-bar angle-iron screen frames so that the said screen frames will be loosely supported on the angle irons of the separator frame in such a manner that the screens will be held in place but may vibrate freely under percussive jarring action, the screen supports themselves being preferably more or less resilient.

In the accompanying drawings Figure 1 is a bottom view of one of the improved screens. Fig. 2 is a cross section of two of the improved screens and their supports. Fig. 3 is a view similar to Fig. 2 but showing a slightly modified form of screen frame. Fig. 4 is a partial longitudinal section of one of the screens showing the manner in which it is supported at its upper end. Fig. 5 is a detail view showing a slightly modified form of the invention.

Referring to the drawings, the improved screen preferably comprises angle-iron side bars 12 and angle-iron end bars 13 properly secured together at the corners of the screen and preferably by triangular plates 15 riveted to the horizontal flanges of said angle-iron side bars and end bars; and 14 denotes wire mesh screen clothing attached to the screen frame in any suitable manner, as by being riveted thereto. Each screen, between its end bars, comprises a series of elastic cross bars 16 which are preferably of resilient steel, and which may be bowed downwardly or outwardly away from the wire mesh screen clothing, these cross bars being preferably sprung into place with their ends abutted against the vertical flanges of the angle-iron side bars. Thus these bowed cross bars, bearing at their ends against the vertical flanges of the side bars of the screen frame, will, because of their tendency to straighten out, serve to hold the wire mesh screen clothing elastically taut, and notwithstanding that they may be riveted (preferably somewhat loosely) to the horizontal flanges of the angle iron side bars, the stretching strain of the cross bars, coming mostly on the vertical flanges of the angle iron side bars, very largely relieves the attaching rivets of said bars

from strain. These elastic stretching cross bars 16 may be advantageously used in screen frames consisting partly or wholly of flat metal bars, as will be understood from Fig. 5, as well as in angle-iron frames.

The screens are preferably loosely supported in place at their outer edges by means of angle iron bars 17 attached to the side walls 18 of the separator frame, and are also 10 preferably loosely supported at their inner edges on a channel iron angle bar 19. These supporting angle iron bars 17 and 19 are inclined with the separator frame and extend longitudinally of the screens, the 15 channel iron angle bar 19 being in practice supported at its ends on suitable cross bars on the separator frame, or in any other suitable manner. The long channel iron angle bar 19, thus supported at or near 20 its ends, and which in turn supports one side of each of the screens, is somewhat resilient or elastic, so that one side of each screen will be elastically supported thereby, and the elastically supported side of 25 said screen will yield more or less under the impact of the strokes of the vibrating hammers, and thus the screens will be suitably jarred percussively in such a manner as to make the screening operation very effective. The outer sides of the screens are rigidly supported by the angle iron bars 17 which are rigidly attached to the side walls 18 of the separator frame.

To hold the inclined screens in place 35 against the action of gravity the upper angle iron end bars thereof may be hooked into a transverse angle iron supporting bar 20 on the separator frame, or may be otherwise suitably supported. To prevent the 40 outer side bars of the screen frame from becoming disengaged from their supporting outer edge angle iron bars 17 the separator frame is preferably provided with pivoted buttons 21 which will prevent the screens 45 from jumping out of engagement with their outer side supporting bars, while the inner edges of the screens may be prevented from jumping out of the central supporting angle iron channel bar 19 (when not secured there- 50 to by bolts or otherwise) by vibrating hammers, as 22, which may be arranged to strike on impact blocks, as 23, between the inner side bars of the screen frames, as indicated in Fig. 2, or they may strike directly on 55 the flanges of the channel bar, as indicated in Fig. 3, the lift of the hammers from said blocks or from the flanges of the inner side bars may be, in such case, less than the depth of the vertical flanges of the angle 60 iron side bars extending into the angle iron bars 17. The vertical flanges of the supporting angle iron bars 17 and 19 will preferably be higher or of greater vertical extent than the vertical extent of the flanges 65 of the angle iron side bars of the screen

frames, so that the last-named flanges will not touch the bottoms or horizontal portions of the supporting angle iron bars; and the screens may thus rest more or less loosely in place so as to be free to be vibrated by the percussive strokes of the vibrating hammers. In cases, however, where the utmost resiliency of the screen frames is not required the said frames may be bolted or otherwise rigidly secured to their supports. 75

The angle irons comprising the screen frames will preferably be of the tri-flange type shown more clearly in Fig. 3, but may be of the right-angular bi-flange type shown in Fig. 2. By using angle irons of the tri-flange type the flanges projecting above the level of the wire mesh screen clothing will serve, in a degree, to prevent the escape of material from the sides of the screens, but should any such material escape from the 85 sides of the screens it will pass down the channels afforded by the side and central angle iron bars 17 and 19.

Although it is preferred to construct the screen frames throughout of angle irons it 90 may sometimes be advantageous to make the screen frames partly of angle irons and partly of flat irons. This whole screen frame plan, with its resilient supports, is designed in every part to afford a separator 95 construction in which the screens will be more resilient than in any other similar separator construction heretofore devised.

The term "angle iron" as herein used will be understood to refer to angle bars 100 preferably of steel rather than iron, and will also be understood to refer to either a bi-flange or a tri-flange construction, as also to a channel iron construction, as the angle iron channel bar 19, or the side-supporting 105 angle iron bars 17.

The improved screen frames, while not being expensive to make, are, above all, very resiliant when percussively vibrated and in addition to being very durable, are capable 110 of being mounted in place in such a manner as to secure the highest efficiency in a separator.

The invention is not to be understood as being limited to the details herein shown, or 115 to any particular means for supporting the screen frames, since they may be secured in place in the separator in any suitable or desired manner.

Having thus described my invention I 120 claim and desire to secure by Letters Patent:

1. A separator screen consisting of a rectangular metallic frame and wire mesh clothing stretched thereon, combined with bowed elastic cross bars for holding the said 125 screen clothing under elastic tension.

2. A separator screen consisting of a rectangular metallic frame, comprising side bars, and end bars, and wire mesh clothing stretched on said frame, combined with 130

- stretching means arranged between said end bars and forming parts of the screen frame itself, said stretching means acting outwardly on said side bars, and serving to hold 5 said screen clothing under elastic tension.
2. A separator screen consisting of a rectangular metallic frame and wire mesh screen clothing attached to the upper side thereof, combined with elastic cross bars attached to the under side of said frame and serving to keep the said screen clothing under elastic tension.
3. A separator screen consisting of an angle iron frame and wire mesh screen clothing stretched thereon, said screen frame comprising resilient bowed cross bars the ends of which abut against the vertical flanges of the angle iron side bars of the frame.
- 10 4. A separator screen consisting of an angle iron frame and wire mesh screen clothing stretched thereon, said screen frame comprising resilient bowed cross bars the ends of which abut against the vertical flanges of the angle iron side bars of the frame.
- 15 5. A separator screen consisting of an angle iron frame and wire mesh screen clothing stretched thereon, combined with angle iron frame supports into which the said screen frame is adapted to hook.
- 20 6. A separator screen consisting of an angle iron frame and wire mesh screen clothing stretched thereon, combined with angle iron frame supports into which the said screen frame is adapted to hook, said 25 screen frame comprising resilient bowed cross bars the ends of which abut against

the vertical flanges of the angle iron side bars of the frame.

7. In a separator, a plurality of screens each of which consists of an angle-iron frame and wire mesh screen clothing stretched thereon, combined with the side pieces of a separator frame, angle-iron supports attached to said side pieces and sustaining the outer edges of said screens, and 35 a channel angle-iron support sustaining the inner edges of said screens.

8. In a separator, a plurality of screens each of which consists of an angle-iron frame and wire mesh screen clothing 40 stretched thereon, combined with the sides of a separator frame, angle-iron supports attached to said side pieces sustaining the outer edges of said screens, a channel angle-iron support sustaining the inner edges of 45 said screens, means, at the inner edges of said screens, for percussively jarring the latter, and means for preventing the disengagement of said screens from their supports under percussive jarring action.

50 In testimony whereof I affix my signature, in presence of two witnesses.

THOMAS LEGGETT STUETEVANT.
